UNITED STATES PATENT OFFICE.

FRANK J. SEABOLT, OF SCHENECTADY, NEW YORK, ASSIGNEE, BY DIRECT AND MESNE ASSIGNMENTS, TO SERVICE CLOCK COMPANY, INC., A CORPORATION OF NEW YORK.

ELECTRIC CLOCK-SETTING MEANS.

Application filed January 2, 1914. Serial No. 809,849.

To all whom it may concern:

Be it known that I, FRANK J. SEABOLT, a citizen of the United States, residing at Schenectady, in the county of Schenectady, State of New York, have invented certain new and useful Improvements in Electric Clock-Setting Means, of which the following is a specification.

My invention relates to electrically controlled clocks or the like, and has for its object the provision of means whereby devices of this general character are automatically set from a remote point in a simple and reliable manner.

My invention relates more specifically to the control of clocks or the like which are connected to electric light or power circuits one of the objects of my invention being to provide means whereby such a clock or any number of such clocks may be automatically set from a remote point by temporarily changing the condition of the circuit, as for instance, by opening the circuit or dropping the voltage for an instant.

My invention is particularly applicable to clocks which are automatically wound at intervals from an electric lighting circuit. Such a clock is disclosed in a patent application filed by Eugene Pons, Serial No. 711,444, filed July 25, 1912. In said application there is described a clock in which at a definite time, as indicated by the hands of the clock, the circuit of an electric motor is automatically closed to wind the clock mechanism. This winding would ordinarily occur at a definite time every day. One of the objects of my invention is to automatically set the hands of the clock at the same time or at about the same time that the clock is wound. To this end I provide means whereby an instantaneous change in the circuit, such as an opening or "flash" of the circuit will cause all of the clocks connected to the circuit to have their hands set. In one particular embodiment of my invention I employ a setting device which sets the hands of the clock as it moves in response to a bias or spring tension, the spring or other biasing means being put under strain or tension during the winding operation. This setting device is held under tension by an electromagnet connected to the lighting circuit so that when the circuit is manipulated to de-

energize the magnet, the device will be released and the hands set. All the clocks being arranged in the same way, they will all be set at the same time. In this way a large number of clocks, a hundred, a thousand, or even several thousand, may be automatically set at the same instant by a single instantaneous act affecting the circuit. In fact, it is contemplated that all the clocks connected to the lighting circuit in a town or city may be automatically set by interrupting or otherwise affecting the circuit for an instant at the powerhouse or central station.

In the accompanying drawing illustrating one form of my invention, Fig. 1 is a front view of a clock embodying my invention; Fig. 2 is a diagrammatic view showing the circuit connections; Fig. 3 is a detail view of the setting mechanism; Figs. 4 to 7 show the hand setting fingers in different positions; and Fig. 8 shows a number of clocks connected to a lighting or power circuit.

Referring first to Figs. 1 and 2, it will be seen that I have illustrated an electrically wound clock of the type shown and described in the application above referred to. This particular arrangement, exclusive of the setting feature, forms no part of my present invention, but in order that a better understanding of the invention as a whole may be had I shall explain the whole clock mechanism in detail. In Figs. 1 and 2, therefore, M indicates an electric motor having an armature A and a series field F which winds the clock spring (not shown). The spring has its inner end secured to the shaft 10 and is wound by turning this shaft by means of a pinion 11, gearing 12 and main gear 13 secured to shaft 10. The outer end of the spring is secured to the spring drum (not shown) in the well known manner. The rotation of the motor will therefore rotate the shaft 10 and wind the clock spring and as the clock runs down the spring drum will of course rotate and transmit its power to the clock mechanism in a manner well understood. In order to control the motor circuit so that, when the spring runs down a certain amount, the motor circuit will be closed and, when it is properly wound up, the motor circuit will be opened, I provide two contact members, one of which is driven by the shaft 10 and the other by the spring

drum. One of these members is secured to the gear 13 and consists of a flat disk 14 of insulating material upon which is mounted the disk 15 of metal, such as brass. 5 This metallic disk is cut away to receive the plate 16 of insulating material. This plate is segmental in shape and is provided at its outer edge where it joins the metal disk with a rib or flange 17. This segmental 10 plate is so arranged with reference to the disk and the shaft 10 that the rib 17 is eccentric with reference to the shaft. The main body of the plate 16 is flush with the surface of the metallic disk and the rib does 15 not extend all the way around the edge of the segment but leaves portions 18 and 19 at the ends of the rib at which the conducting and insulating surfaces are flush. A brush 20 engages the edge of the disk 15. The 20 other conducting member is a spring finger 21 which is driven by the spring drum.

The spring finger 21 engages the flat surface of the other conducting member and is 25 yieldingly held in contact therewith. This finger is likewise adjacent the rib 17 so that it will be deflected by the rib as the contacting members rotate with reference to each other. By referring to Fig. 2 the operation 30 of the two contacting members will be clearly understood. Assuming that the finger 21 is in the position shown, the spring has just been wound and the finger has snapped over the edge of the rib 17 and opened the motor circuit. As the spring runs down the 35 finger will be carried around on the inside of the rib by the rotation of the spring drum to which the finger is attached and since the rib is eccentric, the finger will be placed under tension. When the finger reaches the 40 end of the rib it will snap over the end of the rib across the flush surface 18 into engagement with the conducting surface of the disk 15. If the motor now operates it will rotate the gear 13 which will rotate the 45 shaft 10 and wind the spring and will turn the rib in the same direction that the brush was rotated, viz, a clockwise direction, thereby causing the finger 21 to slide around the outside of the rib and be placed under tension as before until it snaps over the end 50 of the rib, across the flush surface 19 to its initial position and opens the motor circuit. The spring has thus been wound up exactly the amount it has run down. If, however, 55 when the finger snaps over across the flush surface 18 into engagement with the conducting surface of the disk, there is no current or the motor circuit is open at another point (as hereinafter described), then the 60 finger will continue to rotate in contact with the disk for more than one revolution so as to give a long period during which the spring may at any time be wound if current is supplied, and in order to positively stop 65 the clock after a predetermined movement,

I provide the stop element 22. This element is curved as shown and pivoted at 23. When the finger travels around the first time it engages the upper end of the element and moves it inward toward the shaft 70 10, thereby moving the lower end provided with the curved stop surface 24 outward so that the next time the finger comes around it will engage this stop surface and stop the clock. When the motor is now energized, 75 the finger will remain substantially stationary, but the other member will rotate as before in a clockwise direction, the finger sliding around the outside of the rib. When it reaches the end of the rib it will not snap off as before, but it will ride over the upper end of the element 22. When the finger passes the pivotal point of the element it will move it back to the position shown against the stop 25 and continue on 80 around until it finally snaps off the end of the rib. The clock is thus wound up exactly the amount it ran down.

In order that the winding shall occur at a predetermined time of day and occur every day at the same time, I provide another switch independent of the contacting mechanism but in series therewith, which must be closed before the motor can be energized. This switch is controlled by the 90 position of the hands of the clock. To this end the hour hand, which of course moves proportionately to the minute hand, is provided with a gear 26 which meshes with a gear 27 having twice as many teeth as gear 100 26 so that the gear 27 will be rotated once in twenty-four hours. Secured to the gear 27 is a contact member consisting of a conducting disk covered with an insulating material 29 which is cut away part of the way 105 around the edge to expose the conducting strip 30. A brush 31 makes contact with the edge of the disk so as to be in conducting relation with strip 30. A finger 32 to which electrical connection is made by brush 33 operates with strip 30 to close the motor circuit. This finger may be adjusted by the thumb nut 34 so as to change the hour at which contact will be made. All this is described in the Pons application above referred to and requires no further discussion. With this arrangement the clock will be automatically wound every day when the hands of the clock reach a predetermined position, i. e., at a predetermined time. 115

In order to set the hands of the clock every day and set all of the clocks which are connected to the circuit, I provide the arrangement shown in detail in Figs. 3 to 7. This consists of means for moving a hand 120 setting device against the tension of a spring as the clock is being wound. The setting device is such that it sets the hands when it is moved by the spring from one position, which may be called the "operative" posi- 130

tion, to its normal or "inoperative" position. It is held in its operative position by an electromagnetic device connected to the circuit independently of any of the other switches or contacting devices in the clock. In the arrangement shown, a magnet holds the setting device through the agency of a latch so that when the circuit is interrupted or the voltage sufficiently lowered for an instant, the setting device will be released and the hands will be set. In order to operate the setting device to place it under tension, I provide a cam 35 driven by the winding mechanism. As shown, this cam is driven from the gear 13 by pinion 36 on shaft 37. This cam projects backward from the back of the clock, since the hands are set from the back. The minute hand is secured in the usual way to the arbor 38 which extends through the back frame 39 of the clock, and an arm 40 forming a pilot hand is secured thereto so that when the pilot hand is moved the minute hand will be moved accordingly. A lever 41 pivoted at 42 has one end cooperating with an electromagnet 43. This magnet controls a pivoted latch 44 which is drawn away from the magnet by a spring 45 and which engages with the end of the lever 41 to hold it against the tension of spring 46 when the magnet is energized. The circuit of the magnet is closed by bridging the contacts 47, which is done by the lever 41 as it is moved toward the magnet. The opposite end of the lever has an arm 48 pivoted to it and a light spring 49 gives the arm a tendency to move downward from the full line position in Fig. 3. A stop 50 limits the upward movement of the arm. The free end of arm 48 engages with the cam face of the cam 35 and is notched at 51 to receive the cam surface and prevent lateral movement of the arm. In order that the arm 48 and the mechanism attached thereto may return in response to the tension of spring 46 when released at any time regardless of the position of the cam, I cause the arm 48 to return by a different path from that which it traveled when moved by the cam, and thus be free of the cam on its return movement. When the highest point of the cam surface passes under the arm 48, the surface drops off abruptly and frees the arm, whereupon the spring 49 forces the arm downward until its free end engages the guide surface 52. Upon its return movement, the spring 46 forces the arm up the inclined surface 52. In case the cam should be in such position that the arm would strike the side of the cam and not be able to engage the cam face, it will remain in this position until the clock winds again, whereupon the arm will move up against the stop 50 as soon as the lowest position of the cam comes adjacent the arm and the cam surface will fit into the notch 51 of the arm. It will be under-

stood that the cam may make several revolutions while the clock is winding and that there is no certainty as to the position in which the cam will be left when the winding is completed. 70

In Figs. 4 to 7 I have shown a form of setting device which is suitable for my purpose. This consists of a rod 53 pivoted to the lever 41 at 54 and having its opposite end provided with a pin 55 which moves in slot 56 in a plate 57. Pivoted to the pin 55 are two fingers 58 and 59 which are forced apart by spring 60 into the position shown in Figs. 4 to 6, the projections 61 acting to limit the movement. The pin 55 with the fingers pivoted thereto moves back and forth in the slot 56 toward and from the pilot hand 40. In order to close the fingers on the return movement in response to the tension of spring 46, I have provided the guide pins 62 which are square at their lower ends to fit in a transverse slot 63 in the plate while the portions of the pins above the plate are round. The pins are pressed apart by spring 64. On the underside of the fingers cooperating with the projecting portions of the pins are ribs 65. As the fingers move forward the ribs engage the pins and in sliding along them the pins are pressed together as shown in Fig. 7. When the ends of the ribs are reached the pins are released and pressed back to their original position as shown in Fig. 6. In this Figure 6 the parts are shown in the position which they assume when the lever 41 has been moved into engagement with the magnet and latched there, as shown in dotted lines in Fig. 3. When the magnet is deenergized and the rod 53 starts to return, the pins 62 being on the outside of the ribs will force the fingers together and in doing so will adjust the pilot hand 40 as shown in Fig. 7. Upon still further backward movement, the pins will pass the ends of the ribs and the fingers will move back to the position shown in Fig. 4, in which position they will remain until the clock is again wound. It will be noted that the magnet 43 is connected across the line independently of any of the other switches of the clock mechanism. This is shown in Fig. 2. It will moreover be noted that the magnet is only energized when the hand setting device is moved by the winding mechanism and that the magnet is deenergized as soon as the setting device is released. It is also deenergized with a quick break. 115

In Fig. 8 I have shown a number of clocks of the type above described connected to an electric circuit, and a time switch for interrupting the circuit. I have shown this merely for purposes of illustration, since this is a convenient method of opening and closing an electric circuit. It is desirable, of course, that this switch interrupt the cir- 120 125 130

cuit at as near the same time every day as possible—generally at twelve o'clock noon. Any method, however, of interrupting the circuit so as to release the setting device and 5 set the hands at the proper time will come within the spirit of my invention.

The mode of operation of my clock setting arrangement will now be quite apparent. Assuming that it is desired to set the clocks 10 every day at noon, the clocks would be set to wind some time before noon, say, for instance, about three or four minutes before twelve. The winding operation will ordinarily take but a few seconds, so that the 15 hand setting device will be in the position shown in Fig. 6 three or four minutes before twelve. This would allow for the clocks being three or four minutes slow, although ordinarily a clock that is wound and set 20 every day would not run off as much as that. At the proper time the circuit is interrupted and every clock connected to the circuit will automatically be set to its proper position whether they are three or four minutes or 25 less either fast or slow. If through accident or mistake the circuit should not be interrupted, the hands will move until they engage the setting fingers and will then stop. This will be notice that something has gone 30 wrong, although with automatic means for interrupting the circuit there is absolutely no reason why the circuit should ever fail to be interrupted. With this arrangement any 35 number of clocks may be automatically wound and set from a central point so as to indicate the exact time by simply connecting the clocks to the lighting circuit in the same way that a lamp is connected, providing, of course, the circuit is interrupted 40 or the voltage lowered at the proper time. If the setting should be done at a time when the lights are on, the interruption would merely cause a flicker.

While I have described my invention as 45 embodied in concrete form and as operating in a specific manner in accordance with the provisions of the patent statutes, it should be understood that I do not limit my invention thereto, since various modifications 50 thereof will suggest themselves to those skilled in the art without departing from the spirit of my invention, the scope of which is set forth in the annexed claims.

What I claim as new and desire to secure 55 by Letters Patent of the United States, is:—

1. The combination of a clock mechanism, a setting device therefor, an electric motor for winding the clock, a normally energized circuit connected to the motor and setting 60 device, and means whereby the electric motor winds the mechanism at a predetermined time and places the setting device in position to thereafter set the hands on a temporary change of condition in said circuit.

2. The combination of a clock mechanism, a setting device therefor, an electric motor for winding the same, a normally energized circuit connected to the motor and setting device, and means whereby the electric 70 motor winds the mechanism at a predetermined time and places the setting device in position to thereafter set the hands upon an interruption of said circuit.

3. The combination of a clock mechanism, 75 a setting device therefor biased to one position and arranged to set the clock hands in moving to said position, an electric motor connected to said device for moving it to a second position against the bias, and an 80 electromagnet for holding the device in said latter position until released.

4. The combination of a clock mechanism, an electric motor for winding the same, circuit connections thereto, an electromagnetic 85 setting device and means whereby the electric motor winds the mechanism at a predetermined time as indicated by the hands of the clock and places the setting device under the control of the circuit so that the 90 hands of the clock will be thereafter set upon an instantaneous change in the condition of said circuit.

5. The combination with a clock mechanism, an electric motor for winding the 95 same, circuit connection thereto, an electromagnetic setting device and means whereby the electric motor winds the mechanism at a predetermined time as indicated by the 100 hands of the clock and places the setting device under the control of the circuit so that the hands of the clock will be thereafter set upon an instantaneous lowering of the voltage of said circuit.

6. The combination of a clock mechanism, 105 an electric circuit connected thereto, a setting device for said clock and means whereby at a predetermined time as indicated by the hands of the clock the clock mechanism is wound and the setting device connected to 110 the circuit so that it will set the clock when the condition of the circuit is instantaneously changed.

7. The combination of a clock mechanism, and electric lighting circuit connected there- 115 to, a setting device for said clock and means whereby at a predetermined time as indicated by the hands of the clock the clock mechanism is wound and the setting device thereby placed under the control of the circuit so that it will set the clock when the voltage of the circuit is instantaneously lowered.

8. The combination of a clock mechanism, an electric circuit, a setting device for 125 said clock connected thereto and means whereby at a predetermined time as indicated by the hands of the clock the setting device is placed under the control of the circuit so that it will set and release the clock 130

hands when the condition of the circuit is instantaneously changed.

9. The combination of a clock mechanism, an electric motor for winding the same, circuit connections thereto, means whereby the motor automatically winds the clock mechanism at a predetermined time, a setting device for the hands of the clock spring-biased to an inoperative position and arranged to set the hands in moving to said position, means whereby the said device is moved to operative position against the tension of the spring and placed under control of the circuit upon the winding of the 10 clock mechanism, electrically controlled means for holding the mechanism in operative position, and means whereby the setting mechanism is released and the hands automatically set upon a temporary change 15 in the condition of said circuit.

10. The combination of a clock mechanism, an electric motor for winding the same, an electric circuit therefor, means whereby the motor automatically winds the 20 clock mechanism when the hands of the clock reach a predetermined position, a setting device which sets the hands in moving from an operative to an inoperative position and biased to the latter position, means whereby 25 said device is moved to operative position against the bias upon the winding of the clock mechanism, and an electromagnet energized by said circuit upon such movement to hold the said device against the bias until 30 the magnet is deenergized.

11. The combination of a clock mechanism, an electric motor for winding the same, an electric circuit therefor, means whereby the motor automatically winds the 35 clock mechanism when the hands of the clock reach a predetermined position, a setting device which sets the hands in moving from an operative to an inoperative position and biased to the latter position, means whereby 40 said device is moved to operative position against the bias upon the winding of the clock mechanism, and an electromagnet energized by said circuit upon the movement of the device to operative position to hold the said device against the bias until 45 the magnet is deenergized.

12. The combination of a clock mechanism, an electromagnetically controlled setting device therefor, an electric circuit, and 50 means whereby the setting device is connected to the circuit at a predetermined time as indicated by the hands of the clock and sets and releases the hands when the condition of 55 said circuit is changed.

13. The combination of a clock mechanism, an automatic winding mechanism therefor, an electric circuit, an electromagnetic hand setting device and means whereby the operation of the winding mechanism 60 causes the electromagnet of the setting de-

vice to be connected to the circuit, said magnet being deenergized when the setting device operates.

14. The combination of a clock mechanism, an automatic winding mechanism therefor, an electric circuit, an electromagnetically controlled hand setting device biased to a predetermined position and arranged to set the hands in moving to said position and means whereby the operation of the 70 winding mechanism at a predetermined time as indicated by the hands of the clock connects the magnet of the setting device to the circuit and moves the setting element thereof against the bias to a position in which it is held by the magnet so that upon changing the condition of the circuit to decrease 75 the holding power of the magnet, the hands will be set.

15. The combination with a clock mechanism of a hand setting member therefor, a normally energized circuit, an electromagnet connected thereto at a predetermined time as indicated by the hands of the clock 80 for holding the setting member and means whereby the setting member operates to set and release the hands when the circuit is changed to reduce the holding power of the magnet.

16. A setting device for a clock comprising a setting element biased to a predetermined position and arranged to set the hands of the clock in moving to said position, a magnet for holding the setting device against the bias and an electromagnetic device for moving the setting element into the control of the magnet.

17. The combination of a clock mechanism, a setting device therefor normally in a predetermined position which sets the hands in moving to said position, an electric circuit and means connected thereto for moving said device when the hands of the clock reach a predetermined position and for holding it out of its normal position.

18. A setting device for a clock comprising a setting element normally in a predetermined position and arranged to set the hands in moving to said position, an electromagnet for holding the setting device out of its normal position and independent means for moving the setting element into control of the magnet.

19. The combination with the hands of a clock and a normally energized circuit, of electro-magnetically controlled means energized at a predetermined time as indicated by the hands of the clock whereby the hands are set and released upon a subsequent lowering of the voltage of the circuit from normal.

20. The combination of a clock mechanism, a setting device therefor, an electromagnet for holding the setting device in a position from which it will set the hands

- when released, a normally energized circuit connected to said magnet and means whereby at a predetermined time the setting device is moved into the control of the electro-magnet.
21. A combination of a clock mechanism, a setting device therefor which sets the hands in moving from an operative to an inoperative position and biased to the latter position, an electric circuit, means whereby said device is moved against the bias so as to be in operative position when the hands of the hands of the clock reach a predetermined position and an electromagnet energized by
- 5
22. A setting device for a clock comprising a setting element biased to a predetermined position and arranged to set the hands of the clock in moving to said position, a magnet for holding the said device against the bias and means for moving the said element into the control of the magnet.

In witness whereof, I have hereunto set my hand this 31st day of December, 1913.

FRANK J. SEABOLT.
